E. J. D. 1.

UNITED STATES PATENT OFFICE.

FREDERICK A. DILLINGHAM, OF TROY, OHIO, ASSIGNOR TO THE TROY CARRIAGE SUNSHADE COMPANY, OF TROY, OHIO, A CORPORATION OF OHIO.

HINGE.

1,268,793.

Specification of Letters Patent.

Patented June 4, 1918.

Application filed March 20, 1917. Serial No. 155,980.

To all whom it may concern:

Be it known that I, FREDERICK A. DILLINGHAM, citizen of the United States, residing at Troy, in the county of Miami and State of Ohio, have invented certain new and useful Improvements in Hinges, of which the following is a specification.

My invention relates to improvements in swinging sashes and more particularly to wind shields for automobiles, but is also applicable to window sashes and swinging closures for various purposes.

The object of the invention is to simplify the structure as well as the means and mode of operation of such devices whereby they will not only be cheapened in construction, but will be more efficient in use, positive in operation, easily and quickly adjusted and unlikely to get out of repair.

20 A further object of the invention is to provide an improved form of trunnion bracket by which the sash is permitted a limited reciprocatory movement in addition to its oscillatory or swinging movement.

25 A further object of the invention is to provide improved interlocking weather proof joint for the edge of the swinging sash, the interlocking of which is permitted by the reciprocatory movement of the sash independent of its swinging movement before mentioned.

30 With the above primary and other incidental objects in view as will more fully appear in the specification, the invention consists of the features of construction, the parts and combinations thereof, and the mode of operation, or their equivalent, as hereinafter described and set forth in the claims.

40 Referring to the drawings, Figure 1 is an elevation of a portion of an automobile wind shield to which the present invention has been applied. Fig. 2 is a vertical sectional view thereof. Fig. 3 is a side elevation of the trunnion bracket, the trunnion being shown in section, and the relative movement of the bracket being indicated by dotted lines. In the lower portion of said figure the relative movement of the sash due to the swing adjustment of the bracket is likewise indicated by dotted lines. Fig. 4 is an end elevation of the support or trunnion bracket. Fig. 5 is a sectional view of same. Fig. 6 is a top plan view of the base of the

supporting or trunnion bracket. Fig. 7 is 55 a modification.

Like parts are indicated by similar characters of reference throughout the several views.

In the drawings 1, is the frame of the 60 vehicle or supporting standard for the wind shield. In the event the invention is applied to swinging sashes in dwellings or buildings, then the portion 1 represents the window frame surrounding the sash opening. Secured upon the sill 1^a of the opening frame is an upturned flange or tongue 2 extending across the opening. In the drawing this flange or tongue known to the automobile trade as a "fence" is formed of 70 sheet metal bent upon itself into reverse bight with a laterally disposed ledge 2^a and down turned edges upon which the strip rests. This weather strip is secured by screws 3 extending therethrough and into 75 the sill of the opening frame.

Supported within the opening of the frame 1 are two swinging sashes, an upper sash 4 and a lower sash 5. The lower sash 5 is provided on its lower edge with a 80 flanged strip 6 having therein an inverted U shaped or reverse bend 7 within which the upturned flange or weather strip 2 projects when the sash is in its closed position.

As shown in Figs. 2 and 3 the interengaging 85 members 2 and 7 of said weather strip are slightly offset from the plane of the sash on its outer side. It is obvious however that the marginal edge of the sash frame 5 might be formed with an integral groove or recess 90 to receive the tongue or flange 2 as indicated at 8 in Fig. 7. Attached to the side members of the upper and lower sash frame at any suitable point but preferably adjacent to their upper edges, are suitable trunnion 95 members comprising a base or foot portion 10 from which projects an arm 11 carrying a comparatively short trunnion stud 12. The trunnion stud may be of any suitable diameter in proportion to the weight of the 100 sash to be carried. In the drawing however the stud has been shown of comparatively large diameter. It will be understood that the trunnion members are located at opposite sides of the sash in axial alinement 105 one with the other.

Secured to the opening frame or supporting point coincident with the location of the

trunnion members upon the sashes 4 and 5 are suitable supporting brackets. The supporting bracket of the upper sash may be rigid or fixed while that of the lower sash member is capable of a limited swinging movement in a vertical direction.

The lower supporting bracket comprises a base member 13 adapted to be secured to the frame or support 1. This base member is provided with a recess or opening 14 into which projects a trunnion stud or pin 15. The recess 14 is preferably though not necessarily concentric with the trunnion pin 15.

15 In order to strengthen the supporting face it is provided with a lateral swell at a point coincident with the recess as shown in Fig. 6.

Mounted upon the trunnion pin 15 is a 20 split collar or clamping member 16 the interior diameter of which corresponds substantially with the trunnion stud 12, while at one side of the collar and communicating therewith is a recess formed in a lateral 25 extension 17 of the split collar which agrees with the diameter of the trunnion 15. The exterior of the lateral extension 17 is shaped and proportioned to fit within the recess 14 of the base member for swinging movement 30 about the trunnion pin 15. The larger portion of the interior opening of the clamping ring is not exactly circular but is slightly eccentric in the direction of the recessed extension 17. The proportion and arrangement 35 is such that the projected circle or inner circumference of the larger portion of the opening which receives the trunnion 12 and the projected circle or circumference of the recess within the extension 17 will intersect. The clamping ring is capable of a 40 limiting swinging movement to and fro about the pin 15 as indicated by dotted lines in Fig. 3. The trunnion stud 12 of the member carried by the swinging sash is engaged 45 within the larger portion of the recess of the clamping ring while the pin 15 engages in the smaller portion. Being engaged in connecting bays of the same opening the studs 12 and 15 are in peripheral 50 contact one with the other. The parts are securely locked by means of a clamping screw 19 extending through the lugs or ears 20, carried by the swinging ends of the 55 clamping ring 16. The clamping action of the screw 19 not only contracts the split collar or ring upon the trunnion 12 but also draws the trunnion 12 into firm engagement with the pin 15 to effectively lock the parts and prevent rattle or chatter and 60 maintain the adjusted position of the sash.

By referring to Figs. 2 and 3 it will be seen that in its normal position the sash 5 overlaps the weather strip tongue or flange 2. In order to swing the sash either forwardly or rearwardly as desired it is neces-

sary to first elevate the sash out of engagement with the flange 2. This necessitates an upward or reciprocatory movement of the sash before it may be swung upon its trunnion. By first relieving the tension of 70 the clamping ring 16 upon trunnion stud 12 by releasing the clamping screw 19, the sash may be elevated to disengage the tongue and groove joints at its lower edge. In this upward movement of the sash 5 the 75 clamping ring 16 swings about the trunnion pin 15 as shown by dotted lines in Fig. 3 carrying with it the trunnion stud 12 and the sash 5 supported thereon. Upon being disengaged from the weather strip or sill 80 flange 2, the sash may be swung to or fro. Upon its release the weight of the sash returns the split ring or collar of the supporting bracket to its normal position. The return swinging movement of the collar or 85 ring of said supporting bracket is limited by a lip or stop ledge 21 upon the base 13 which engages the side of said split clamping ring or one of the lugs or ears 20 thereof. It will be understood that before the lower 90 sash may be elevated to disengage it from the sill flange 2 the upper sash 4 must be swung slightly out of alignment therewith.

The upper sash 4 is supported in a manner similar to the lower sash except that 95 under ordinary conditions it is not necessarily permitted the vertical or reciprocatory movement independent of its swinging movement. For ordinary purposes a supporting bracket for the upper sash may be 100 employed in which the clamping ring and the base are formed integral. A clamping screw 22 similar to the screw 19 may be employed for contracting the integral split collar 23 upon the trunnion stud of the 105 sash 4 to retain the sash in its adjusted position. From the construction thus described it will be obvious that the sash 5 will be permitted a free independent vertical movement, preparatory to its swinging 110 movement. This vertical movement is compensated for by a yielding or swinging movement or a split clamping ring 16 of the supporting bracket. Inasmuch as there is a differential movement of the split collar 16 115 and the trunnion stud 12 during its limited initial movement the clamping of the split collar about the stud by means of the screw 19 will effectually lock the sash to prevent either reciprocatory or oscillatory movement. After the sash has been adjusted to the desired inclination the contraction of the collar upon the stud will likewise hold the sash in adjusted position while the movable split collar or clamping ring 16 120 will rest upon the lip or ledge 21.

Having thus described my invention I claim:

1. In a hinge construction of the character described, two tangentially positioned 130

trunnion studs, means for separately attaching each stud to a support, and a clamp collar inclosing both studs, substantially as specified.

5 2. In a hinge construction of the character described, two tangentially positioned studs mounted upon different relatively movable members, and means for frictionally retaining said studs in different positions of relative adjustment substantially as specified.

10 3. In a hinge construction of the character described, two eccentrically positioned trunnion studs mounted upon different relatively movable members, and a connecting link engaged simultaneously by both studs and means for simultaneously locking both trunnion studs in adjusted relation with each other, substantially as specified.

15 4. In a hinge connection of the character described, a member having a socket or recess therein, a pivotal stud carried by the member contiguous to said socket or recess, a link seated within the socket or recess and having pivotal movement about said stud, a shoulder upon said member adapted to limit the pivotal movement of the link, and a second member having a pivotal stud engaged with said link eccentrically in relation with

20 the first mentioned stud, said members being adapted to be mounted upon different relatively movable supports.

25 5. In a construction of the character described, two relatively movable members normally engaged in overlapping relation, one of said members being capable of an initial reciprocatory movement out of overlapping relation and a subsequent swinging movement, of a supporting means therefor including two eccentrically positioned trunnion members and a clamping collar common to both trunnions.

6. In a construction of the character described two relatively movable members normally engaged in overlapping relation, one of said members being capable of an initial reciprocatory movement out of overlapping relation and a subsequent swinging movement, of a supporting means therefor including a trunnion member carried by each of the relatively movable members, and a swinging link pivotally engaged with each trunnion member.

7. In a construction of the character described, two relatively movable members normally engaged in overlapping relation, one of said members being capable of an initial reciprocatory movement out of overlapping relation and a subsequent swinging movement, of a supporting means therefor including two pivotal studs adapted to make peripheral contact with the other and clamping means for forcibly engaging one trunnion stud with the other.

8. In a construction of the character described, two relatively movable members normally engaged in overlapping relation, one of said members being capable of an initial reciprocatory movement out of overlapping relation and a subsequent swinging movement, of a supporting means therefor including a bracket carried by one member, a trunnion carried by said bracket, a second trunnion carried by the other member, and a split collar surrounding both trunnions adapted by its contraction to lock the parts in adjusted position.

In testimony whereof, I have hereunto set my hand this 14th day of March A. D. 1917.

FREDERICK A. DILLINGHAM.
